[57] CLAIM

The ornamental design for eyeglasses, as shown and described.

DESCRIPTION

FIG. 1 is a front perspective view of eyeglasses showing my new design;

FIG. 2 is a top plan view thereof;

FIG. 3 is a right elevational side view thereof, the side opposite being a mirror image;

FIG. 4 is a bottom plan view thereof;

FIG. 5 is a front elevational view thereof;

FIG. 6 is a rear elevation view thereof;

FIG. 7 is a perspective view thereof with the lenses and temples omitted for ease of illustration only;

FIG. 8 is a front elevational view thereof;

FIG. 9 is a rear elevational view thereof;

FIG. 10 is a top plan view thereof;

FIG. 11 is a side right side elevational view thereof, the side opposite being a mirror image;

FIG. 12 is a bottom plan view thereof;

FIG. 13 is a perspective view of a second modified embodiment of the design shown in FIGS. 1-12 with the lenses and temples omitted for ease of illustration;

FIG. 14 is a front elevational view thereof;

FIG. 15 is a right side elevational view thereof, the side opposite being a mirror image;

FIG. 16 is a rear elevational view thereof;

FIG. 17 is a perspective view of a third modified embodiment of the design shown in FIGS. 1-12 with the lenses and temples omitted for ease of illustration;

FIG. 18 is a right side elevational view thereof, the side opposite being a mirror image;

FIG. 19 is a top plan view thereof;

FIG. 20 is a bottom plan view thereof; and,

FIG. 21 is a rear elevational view thereof.
